CLAIM

The ornamental design for a valet tray, as shown and described.

DESCRIPTION

The patent or application file contains a least one drawing executed in color. Copies of this patent or patent application publication with color drawing(s) will be provided by the Office upon request and payment of the necessary fee.

FIG. 1 is a perspective view of a valet tray, in an open configuration, showing my new design;

FIG. 2 is a perspective view of the valet tray, in a closed configuration, showing my new design;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The GTFX trademark, shown in FIG. 1 of the claimed design is a registered trademark of Wisteria Sky Pty Ltd ATF Wisteria Sky Family Trust proprietary limited company (p/l).
